CLAIM

The ornamental design for a combined refreshment table and pinball machine casing, as shown and described.

DESCRIPTION

FIG. 1 is a top plan view of a combined refreshment table and pinball machine casing showing our new design;

FIG. 2 is a right side elevational view thereof;

FIG. 3 is a front elevational view thereof;

FIG. 4 is a left side elevational view thereof;

FIG. 5 is a rear elevational view thereof;

FIG. 6 is a bottom plan view thereof;

FIG. 7 is an elevational view similar to FIG. 4 showing a rotating top modification; and

FIG. 8 is an elevational view similar to FIG. 5 showing a rotating cabinet modification.

FIG. 9 is a perspective view of FIG. 1.
